UNITED STATES PATENT OFFICE.

JOSEPH S. BLINN, OF NEW HAVEN, CONNECTICUT.

SUPPOSITORY INJECTOR.

Application filed February 24, 1923. Serial No. 620,996.

To all whom it may concern:

Be it known that I, JOSEPH S. BLINN, a citizen of the United States of America, and a resident of New Haven, in the county 5 of New Haven and State of Connecticut, have invented a new and Improved Suppository Injector, of which the following is a description.

10 My invention relates to an injector or applicator for the insertion of a suppository in a cavity of a human body.

The general object of my invention is to provide a device for the indicated purpose so formed and arranged as to insure the proper insertion and application of the suppository while eliminating the possibility of producing injury, distress or discomfort in the placing of the suppository.

Reference is to be had to the accompanying drawings forming a part of this specification, it being understood that the drawings are merely illustrative of one example of the invention.

25 Figure 1 is a longitudinal section of the body of the injector or applicator, the plunger being omitted and a suppository shown inserted therein;

Figure 2 is a view similar to Figure 1 with the plunger inserted in the body of the injector and the suppository forced to a forward position ready for ejection, the plunger being shown in elevation;

Figure 3 represents an elevation of the cylinder and tip of the injector body;

35 Figure 4 is a front elevation of the injector body on an enlarged scale;
Figure 5 is a side elevation of the injector.

with a protective cap thereon as when the injector is not required for use.

40 In carrying out my invention in accordance with the illustrated example an injector body is provided consisting of a cylindrical

jector body is provided, consisting of a cylinder 10 adapted to receive a plunger 11. The injector body includes a rearwardly

45 The injector body includes a rearwardly flaring bell mouth 13 secured by threads 14 to the cylinder 10. The plunger has its rear end in the form of an eye 15 for receiving a finger in the operation of the plunger.

50 The cylinder 10 is provided with a tip composed of resilient elongated members produced by forming longitudinal slits 16 in the front tapered terminal of the cylinder, the slits being at angles to each other 55 and preferably disposed so as to quarter said tip, thereby producing a plurality of

resilient members 17. The front end of the tip is given a ball formation by producing enlargements 18 on the resilient fingers 17, the enlargements presenting externally rounded lines so that jointly the enlargements are approximately of ball formation particularly when the fingers are not distended. In use the plunger is withdrawn from the cylinder 10 and a suppository A placed in the rear end. The plunger 11 is now inserted in the cylinder 10 through the flaring bell mouth 13 to advance the suppository A to the front end of the tapered terminal of the cylinder 10 as shown in Figure 2 so that the suppository is disposed between and lightly gripped by the resilient fingers 17. The device is now inserted in the cavity of the body and the plunger 11 moved forwardly to force the suppository A through the tip of the cylinder 10, the resilient members 17 yielding to the pressure. The enlargements 18 in the insertion of the injector into the body, prevent any possible pricking or laceration of the internal walls of the cavity. The resilient members 17 have the further function of preventing the suppository from being pressed back into the device. Said resilient members normally slightly converge and therefore the front edges of said members at the enlargements 18 have a slight tendency to dig into the material of the suppository and prevent its retrograde movement.

The flaring bell mouth 13 constitutes a stop limiting the insertion of the device into the cavity to be treated. The bell mouth 13 is formed rigid with a forwardly extending tubular element 12 and the threaded connection 14 permits of the longitudinal adjustment of the tubular element 12 on the cylinder 10, thus varying the effective length of the device. The adjustment of the element 12 on the cylinder 10 is independent of the plunger and the varying of the length of the body formed jointly by the cylinder 10 and element 12 does not vary the forward movement of the plunger 11 because in all cases said forward movement is limited by a shoulder or collar 111 contacting with the rear end of cylinder 10.

When the injector is not in use a cap 19 is placed on the front end thereof. Said cap 19 has a tight fit on the tapered surface of element 12 of the bell mouth 13 and in addition the interior of the cap at the front end

is formed of reduced diameter as at 20, there being a slightly bevelled shoulder 21 at the entrance to the zone 20 of reduced diameter. The purpose of the described cap formation is to insure frictional engagement between the interior of the cap 19 at the front end with the rounded surfaces of the enlargements to aid in holding the cap in position.

10 I would state in conclusion that while the illustrated example constitutes a practical embodiment of my invention, I do not limit myself strictly to the exact details herein illustrated, since, manifestly, the same can 15 be considerably varied without departure from the spirit of the invention as defined in the appended claims.

Having thus described my invention, I claim:

- 20 1. As a new article of manufacture, a suppository injector comprising a cylinder, a flaring bell mouth on said cylinder at the rear end said bell mouth at its rear end constituting a stop flange to limit the inward movement of the injector into the cavity, a 25 tapered tip on said cylinder comprising a plurality of resilient elongated members, the forward ends of said fingers having enlarged laterally protuberant front ends presenting longitudinally rounded external

surfaces to give an approximate ball formation to the front end of the injector, and a plunger adapted to be inserted into the cylinder through the said bell mouth for forcing a suppository through the resilient members. 35

2. As a new article of manufacture, an injector for suppositories comprising a body, a plunger operating in said body, resilient members on the body at the front end and 40 formed with enlargements at their forward extremities, and a cap the rear end of which tightly fits said body, said cap having internally at its front end a zone of reduced diameter as well as a bevelled shoulder at 45 the entrance to said zone of reduced diameter to frictionally engage the enlarged extremities of resilient members.

3. As a new article of manufacture, a device of the class described including a tubular element having a through bore for the passage of a suppository, resilient members on said element at the front end and normally convergent, and a plunger operating in said tubular element, said resilient members having enlarged front ends presenting annularly disposed lateral protuberances having longitudinally rounded exterior surfaces. 50 55

JOSEPH S. BLINN.
